(57) **CLAIM**

The ornamental design for a handle for a surgical instrument as shown and described.

DESCRIPTION

FIG. 1 is a left, front, perspective view of a handle for a surgical instrument in accordance with the present design; FIG. 2 is a left, side view of the handle for a surgical instrument of FIG. 1;

FIG. 3 is a top view of the handle for a surgical instrument of FIG. 1;

FIG. 4 is a right, side view of the handle for a surgical instrument of FIG. 1;

FIG. 5 is a bottom view of the handle for a surgical instrument of FIG. 1;

FIG. 6 is a front view of the handle for a surgical instrument of FIG. 1; and,

FIG. 7 is a rear view of the handle for a surgical instrument of FIG. 1.

The broken lines shown in the drawings illustrate portions of the handle for a surgical instrument that form no part of the claimed design.

1 Claim, 4 Drawing Sheets
